HAIR COMB

Albert Safianoff, Palos Verdes Estates, Calif., assignor to
The Gillette Company, Boston, Mass., a corporation of Delaware

Filed Nov. 23, 1962, Ser. No. 72,585

Term of patent 14 years

(Cl. D86—8)

FIG. 1 is a view in front elevation of a hair comb showing my new design;

FIG. 2 is a view in side elevation;

FIG. 3 is a view in section taken along line 3—3 of FIG. 1;

FIG. 4 is a view in section taken along line 4—4 of FIG. 1;

FIG. 5 is a view in section taken along line 5—5 of FIG. 1; and

FIG. 6 is a view in section taken along line 6—6 of FIG. 1.

I claim:

The ornamental design for a hair comb, as shown.
